Primary Examiner — Sandra Snapp*Assistant Examiner* — Anehita E. Oribabor(57) **CLAIM**

The ornamental design for an electrical outlet box substantially as shown and described.

DESCRIPTION

FIG. 1 is a top perspective view of an electrical outlet box showing our new design;

FIG. 2 is a top plan view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The dash-dash broken lines illustrate portions of the electrical outlet box that form no part of the claimed design.

1 Claim, 7 Drawing Sheets(56)
